(57) **CLAIM**

The ornamental design for a lottery terminal as shown and described herein.

DESCRIPTION

FIG. 1 is a front perspective view of a lottery terminal of our new design.

FIG. 2 is a left side view of the lottery terminal of FIG. 1, the right side view being a mirror image thereof.

FIG. 3 is a front view of the lottery terminal of FIG. 1.

FIG. 4 is a rear view of the lottery terminal of FIG. 1.

FIG. 5 is a top view of the lottery terminal of FIG. 1; and, FIG. 6 is a bottom view of the lottery terminal of FIG. 1. The dashed broken lines in the drawings illustrate portions of the lottery terminal that form no part of the claimed design.

1 Claim, 6 Drawing Sheets
